UNITED STATES PATENT OFFICE

90,975

DESIGN FOR A LAMP STAND OR SIMILAR ARTICLE

Herman E. De Vries, New York, N. Y., assignor to H. T. Cushman Mfg. Co., North Bennington, Vt.

Application May 24, 1933. Serial No. 48,206

Term of patent 3½ years

To all whom it may concern:

Be it known that I, HERMAN E. DE VRIES, a citizen of the United States, residing at New York city, in the county and State of New York, have invented a new, original, and ornamental Design for a Lamp Stand or Similar Article, of which the following is a specification, reference being had to the accompanying drawing, forming a part thereof.

The figure is a perspective view of a lamp stand showing my design.

I claim:

The ornamental design for a lamp stand or similar article, as shown.

HERMAN E. DE VRIES.
